US00D691174S

(12) **United States Design Patent**
Lipman et al.

(10) **Patent No.:** **US D691,174 S**
(45) **Date of Patent:** **** Oct. 8, 2013**

- (54) **DISPLAY WITH A GRAPHIC USER INTERFACE**
- (75) Inventors: **Kelley J. Lipman**, Livermore, CA (US); **Robin S. Gaffney**, Redwood City, CA (US); **Kimberly J. Tansey**, San Carlos, CA (US); **Arna D Ionescu**, San Francisco, CA (US); **Graham MacDonald Hicks**, San Francisco, CA (US)
- (73) Assignee: **Intuity Medical, Inc.**, Sunnyvale, CA (US)
- (**) Term: **14 Years**
- (21) Appl. No.: **29/411,247**
- (22) Filed: **Jan. 18, 2012**

(57) **CLAIM**

The ornamental design for a display with a graphic user interface, as shown and described.

DESCRIPTION

The FIGURE is a front view of a display with a graphic user interface showing the new design.

The broken line showings of the display, circles, vertical lines, and oval are for the purpose of illustrating environmental structure and portions of the display with a graphic user interface and form no part of the claimed design.
